CLAIM

We claim the ornamental design for an "adjustable cable slitting tool," as shown and described herein.

DESCRIPTION

FIG. 1 is a perspective view of an adjustable cable slitting tool in accordance with the present design.

FIG. 2 is a back elevational view of the adjustable cable slitting tool seen in FIG. 1.

FIG. 3 is a left side elevational view of the adjustable cable slitting tool seen in FIG. 1.

FIG. 4 is a front elevational view of the adjustable cable slitting tool seen in FIG. 1.

FIG. 5 is a right side elevational view of the adjustable cable slitting tool seen in FIG. 1.

FIG. 6 is a top plan view of the adjustable cable slitting tool seen in FIG. 1; and,

FIG. 7 is a bottom plan view of the adjustable cable slitting tool seen in FIG. 1.
